UNITED STATES PATENT OFFICE.

THOMAS M. CHANCE, OF PHILADELPHIA, PENNSYLVANIA.

COAL-WASHING AND ORE CONCENTRATION.

1,224,138.

Specification of Letters Patent.

Patented May 1, 1917.

Application filed October 2, 1915. Serial No. 53,761.

To all whom it may concern:

Be it known that I, THOMAS M. CHANCE, a citizen of the United States, residing at Philadelphia, in the county of Philadelphia 5 and State of Pennsylvania, have invented a certain new and useful Improvement in Coal-Washing and Ore Concentration, whereof the following is a specification.

My invention relates to a method of washing coal and concentrating ores in which materials of different specific gravity are separated by immersion in a fluid mass of specific gravity great enough to effect the flotation of that portion of said materials of 15 lower specific gravity.

By the term "fluid mass" I mean to include any mixture of comminuted solids and liquid, which when properly agitated will approach the properties and fluidity of a 20 true liquid. Such a liquid mass may be produced by properly agitating a mixture of sand and water, the desired specific gravity of the agitated mixture being secured by proper dilution of the sand.

25 In carrying out my method the apparatus used may be greatly varied and the accompanying drawings are merely representative of the general association of elements necessary to the operation of said method.

30 It is well known that if a mixture of coal and slate be introduced into a saturated solution of zinc chlorid the coal will float to or near the surface of said solution and the slate will sink to the bottom of the container.

35 Processes involving the use of such solutions of high specific gravity have never proven of commercial value in the cleaning of coal, and their use has been restricted to the laboratory determination of the physical characteristics of various fuels.

40 The great difficulty hitherto encountered in the application of this principle to the concentration of ores and washing of coal has been that in all cases the fluid used was a liquid solution of either great economic value, or else possessed of characteristics deleterious to the resultant product. For it will be readily understood that a portion of the solution will be inevitably carried over with

45 the separated materials, either mechanically or occluded within the pores of the individual grains of said materials, and while some of the solution so lost might be recovered, the cost of such recovery would in most 50 cases preclude the use of the method.

The characteristic of my invention is that

the fluid mass, which I use as a vehicle of high specific gravity for the separation of materials of different specific gravity, is in no sense a solution of a solid, or salt, in a liquid, but is a true mechanical mixture of a comminuted solid with a liquid, said mixture being caused to assume the characteristics and properties of a liquid by agitation. To this end the receptacle or tank in which 60 said separation is to be effected is provided with means for keeping said fluid mass properly agitated and is also provided with means for the removal of the separated materials from said fluid mass after separation has 65 been accomplished. The tank having been filled to the proper level with said agitated fluid mass, the material to be separated is introduced into said mass and that portion of the material of greater specific gravity 70 than said mass immediately sinks to the lower portion of the mass and is removed from the tank by the means provided to that end, while that portion of said material of a specific gravity approximating, or less 75 than, that of said fluid mass rises to, and is removed from, the upper portion of said mass. In the foregoing description the separation is secured by reason of gravitational attraction, but it will of course be understood 80 that the method may be carried out under conditions in which the action of centrifugal force is substituted for that of gravity.

In the accompanying drawings I have illustrated diagrammatically five types of 90 apparatus to carry out my method. All of the drawings are vertical cross-sectional views. Figure I illustrates an apparatus in which agitation of the fluid mass is accomplished by mechanical means. Fig. II 95 shows an apparatus in which agitation is produced by the introduction of hydraulic water. Figs. III and IV are vertical cross-sections illustrating the application of the method to jigs of the types in common use, 100 and Fig. V is a similar cross-section illustrating a type of apparatus in which air may be employed as a means for effecting agitation of the fluid mass. Like numbers indicate like parts in the drawings.

105 In the drawings, Fig. I, 1 indicates a water-tight tank adapted to contain the fluid mass, in which an agitator 2, carried in suitable bearings, is driven by a pulley 3. The material to be separated is fed into said 110 tank 1 through a feeding device 4. An elevator 5 is provided for removing the sep-

rated material of lower specific gravity from said tank 1, said elevator discharging said material over a dewatering screen 6, and an elevator 7 is provided for removing the 5 separated material of higher specific gravity from said tank 1, said elevator discharging said material over a dewatering screen 8. Said elevators 5 and 7 are preferably provided with dewatering buckets or other 10 means whereby a minimum amount of said fluid mass is delivered on said screens 6 and 8 in discharging the separated materials from tank 1, and said screens 6 and 8 are provided with collecting boots 9 and 10 which are connected to tank 1, either by a 15 chute or through a pump, for the return of that portion of said fluid mass passing through said screens 6 and 8. 11 is a spigot for flushing tank 1.

20 The operation of the method when using this apparatus for the washing of coal is as follows:

Assuming the tank 1 to be partially filled with a fluid mass consisting of a mixture 25 of sand and water, agitation of said mass is produced by the revolution of the agitator 2 through the medium of pulley 3. If sufficient sand be added to the water to produce a specific gravity of the fluid mass of 30 about 1.6, and a mixture of coal of a specific gravity approximating 1.45 and slate of about 2.3 specific gravity be introduced 35 through the feeding device 4 into said fluid mass, the slate will immediately sink to the bottom of tank 1 and be lifted out of said tank through the elevator 7. The coal being of less specific gravity than the fluid mass will rise to the upper portion of said mass and be removed therefrom by elevator 40 5. That portion of the fluid mass mechanically carried over by elevators 5 and 7 is reclaimed in passing over dewatering screens 6 and 8, with or without the assistance of wash-water, and falls into the 45 boots 9 and 10 from which it is removed and returns to tank 1. In the operation of the apparatus the mechanical losses of the fluid mass, that is, that portion of said mass carried away by the slate and coal, may be 50 made up by the addition to tank 1 of fresh sand and water.

In the drawing, Fig. II, 1' indicates a water tight tank adapted to contain the fluid mass into which the material to be separated is fed through a feeding device 4'. An elevator 5', in this case a dewatering wheel, is provided for removing the separated material of lower specific gravity from said tank 1', said elevator discharging 55 said material over dewatering screen 6', and an elevator 7' is provided for removing the separated material of higher specific gravity from said tank 1', this elevator discharging 60 said material over dewatering screen 8'. As 65 before described, said elevators 5' and 7' are

preferably built as dewatering elevators, and the screens 6' and 8' are provided with collecting boots 9' and 10' for the return of that portion of the fluid mass reclaimed by said screens. 11' is a spigot for flushing the lower part of compartment 12. 12 is a diffusion compartment for causing even flow through said fluid mass of the hydraulic water introduced through valve 13 and pipe 14 for agitation, by means of baffles 15.

The operation of the method when using this apparatus for the washing of coal is similar to that described for the apparatus shown in Fig. I, with the exception that agitation of the fluid mass is produced 70 through the medium of a rising current of water introduced through hydraulic water pipe 14, instead of by mechanical stirring device 2. Tendency of the hydraulic water to "boil" or flow unequally through the fluid 75 mass is hindered by the diffusion compartment 12. This compartment is filled with baffles, shown in this case as a layer of stone 80 placed between two sieves, and these baffles tend to promote even upward flow 85 and prevent local currents of the hydraulic water through the fluid mass above. It will 90 of course be understood that the hydraulic water, introduced through pipe 14, may itself be a portion of the fluid mass, that is, it may 95 consist of a mixture of sand and water, being used over and over again; or it may consist of clear water from an external supply.

All of the drawings show outlets O from the boots 9 and 10 for the discharge of the 100 liquid and comminuted solid matter removed from the separated material by the screens 6 and 8, and these may be connected by pipes or conduits p, p, as shown by Figs. I and II, and the liquid, etc., elevated by any 105 type of elevator, or pump, as illustrated diagrammatically by the centrifugal pump C shown by Fig. II, and discharged through the pipe or conduit d, d, into the receptacle 1', either directly, or through the feed hopper 4' as shown.

The apparatus operated as shown by Fig. II, will thus be using the same mixture forming the "fluid-mass" over and over again, but as there will always be some loss 110 of liquid and also of comminuted solid material, which is carried away adhering to the separated materials, it will be understood that like quantities of water and comminuted solid material will be added to the 115 fluid mass contained in the receptacle 1, (1', 1^a or 1^b) to make up for such loss and to maintain the quantity and the specific gravity of the "fluid-mass" nearly constant, so that the specific gravity of the fluid-mass 120 will always be greater than one and less than another of the materials that are to be separated.

Figs. III and IV illustrate this method of separation by means of apparatus similar to 125

- standard forms of jigs, in which the material to be separated and the fluid mass are moved relatively one to the other by motion imparted by jig mechanism in common use.
- 5 To make it clear that no jiggling action is necessary, I have shown the apparatus without the sieves which in jiggling are necessary for the support of the jig-bed, but it will of course be understood that sieves for controlling the flow in the hutch may be used if desired as illustrated by Fig. II.
- Fig. III shows a plunger jig of the fixed sieve type, commonly known as the Hartz jig from which the sieve has been removed.
- 10 15 In this drawing 16 is the receptacle for the fluid mass, 17 is a plunger operated by the eccentric 18, 19 is a feed hopper for material to be separated and also for material of which the fluid mass is composed, 20 is an overflow for separated light material and 21 is an elevator for removing separated heavy material, and 6^a and 8^a are separating screens for removing the insoluble comminuted material and liquid from the separated materials.
- 25 30 35 Fig. IV shows a movable sieve jig in which the apertures of the sieve are made large enough to permit the largest particles to pass freely through them, the sieve thus no longer performing the functions of a sieve, but being used as a means to agitate the fluid mass. In this drawing 28 is the receptacle for the fluid mass, 22 a movable sieve or agitator, to which other sieves as shown by 23 may be attached, 24, 24, 25 are eccentrics by which the agitator is operated, 25 is the feed hopper, 26 is an overflow discharge for separated light material, 27 an elevator for removing separated heavy material, and 6^b and 8^b are screens for removing the insoluble comminuted material and liquid from the separated materials.
- 40 45 50 Fig. V is similar in many of its parts to the apparatus shown by Fig. I as indicated by the reference numbers referring to those parts, but it is provided with a hollow shaft 30, which may be rotated by means of the pulley 3 and is free to rotate in a stuffing box 31 fixed in position on a platform or supporting cross piece 32, and may thus be supplied with air under pressure through the pipe 33 from any source of supply of air under pressure. The hollow shaft 30 is connected with hollow radial arms 34 closed at the ends but provided with small perforations 35 for the escape of air as jets of small diameter. The operation of the method with this apparatus is similar to that of apparatus already described, the fluid mass being agitated by air.
- 60 65 While in the foregoing description of the operation of the method the fluid mass was described as being an agitated mixture of sand and water, it will be understood that any mixture of suitable consistency of a comminuted solid and a liquid may be used,

provided the specific gravity of the resultant fluid mass is less than that of one of the constituents to be separated and that it approximates, or is greater than, that of the other constituents.

The comminuted solid used for producing the fluid mass preferably will be composed of grains smaller than the average size of the material that is to be floated and of greater specific gravity than this material, and these grains, which with the liquid used comprise the fluid mass, should not be widely separated. It may be composed of sand, crushed waste, or other material of suitable properties. If the method be used in the concentration of ores, finely comminuted middlings or concentrates may be employed.

In the accompanying drawings the various adjunctive devices shown for the operation of the method are intended to represent the general association of elements necessary to such operation, but I do not limit myself to the use of the forms shown. As before stated, the apparatus necessary to the operation of the method must always consist of the following elements: A receptacle adapted to contain a fluid mass, said mass consisting of an agitated mixture of comminuted solid matter and liquid, means for agitating said fluid mass, means for introducing the material to be separated into said fluid mass, and means for the removal of the separated materials from said fluid mass after separation has been accomplished. It will be understood that the receptacle may be of any desired shape or form and that one or more such receptacles may be employed. The means shown in the drawings for the removal of the separated materials from the fluid mass are intended to be typical of elevating devices in common use, as any other forms, such as belt conveyers, scraper lines, sand wheels, etc., may be readily used. In certain cases the means employed to these ends may do away with such elevating devices entirely, the separated material of lower specific gravity being floated out of the receptacle—as in some forms of jigs—and that of higher specific gravity being trapped out of the machine periodically, in the same manner that the slate is trapped out of the hutches of coal jigs and washers. The feeding device may be of any of the forms in common use, although feeders of the type in which the material is fed in a thin stream are preferable, and the feed may be introduced either above or below the surface of the fluid mass, and at either the center or the edge of the receptacle containing said mass. The agitation of the fluid mass may be produced mechanically by any type of stirring, or shaking, apparatus, or by the addition of hydraulic water, with either a uniform or

- pulsating flow. Similarly, air may be introduced into the fluid mass for the purpose of agitation as is commonly practised in cyanid agitation tanks, and this air may have 5 either uniform or pulsating flow. In some cases it may be desirable to produce the agitation of the fluid mass by causing said mass and the material that is to be separated to move relatively to each other. Such relative 10 movement may be accomplished by using apparatus similar to the standard plunger jig with fixed sieve, the operation of which is illustrated by Fig. III and will be understood without further description, or by 15 means of apparatus similar to the types of movable sieve jigs in common use, the operation of which is illustrated by Fig. IV and will be understood without further description.
- 20 If too large a portion of the fluid mass is carried away by the separated material, this may in many cases be removed from said material by the use of wash water, or by passing the material over screens or through 25 any of the standard types of upward current hydraulic classifiers. The comminuted solid used for producing the fluid mass will generally be so very much smaller than the material separated that it can be lifted 30 by a current of water that will not disturb said material to any degree. Washing or classifying devices of this kind may be constructed integrally with the apparatus or may be separately used as auxiliaries.
- 35 It is desirable that the specific gravity of the fluid mass be kept constant within certain limits and to accomplish this result the apparatus may be provided with means for increasing or reducing the percentages 40 of comminuted solid material and liquid in said mass. It may in some cases be advisable to make such means automatic, and this may be readily accomplished by any one skilled in the art by the use of floats of 45 proper specific gravity linked to the source of supply of either the liquid or the comminuted solid or of both. A discharge weir in the tank containing the fluid mass may be used if desired, to keep said mass from 50 rising above a predetermined height.
- It should be pointed out that while in some embodiments of apparatus for carrying out the method a current of hydraulic water, or of an elastic fluid such as air, is 55 used for the agitation of the fluid mass, such current is only strong enough to secure proper agitation of the finely comminuted solid and is not in any case intended to produce a classifying or concentrating action upon the relatively large material that is to be separated.
- As the separation is produced purely by flotation, the relative size or shape of the different grains of the material that is to 60 be separated will have little or no effect in

the separation; and the grouping of large grains of light material with small grains of heavy material, by their falling velocity,—as in jigging or classifying,—is not made use of in any way. Hence one of the greatest 70 difficulties that is ordinarily encountered in coal washing or ore-dressing—the mixing of thin, flat grains of heavy material with grains of much lower falling velocity, due to the heavy grains being caught on their flat side by the separating current, and the reverse case, in which flat light grains fall endwise through a current that should lift them—is eliminated. Another great advantage of the method is that the materials 75 after separation are in positions relatively remote from each other, therefore the difficulty ordinarily encountered in securing clean discharges from jigs, due to the close and varying line of contact between the refuse and the jigged product, is not met with. 80 The use of mixtures of finely divided solids, such as clays, with water, in upward current classifiers is known. Such materials when finely divided form suspensions in 90 water that approach solutions in their physical properties and hence it is exceedingly difficult to separate the concentrated product from mixtures of this kind. It will of course be understood that it is impossible 95 to obtain comminuted materials, either natural sands or sands mechanically produced, that will contain no trace of such finely divided material, and the expression mixture of "appreciably coarse granular material" 100 as used in the claims hereof is intended to mean mixtures of comminuted insoluble material and liquid possessing physical characteristics that in no sense approach suspensions or solutions, but that require continuous agitation to assume and preserve the fluidic properties herein described and claimed.

It will of course be understood that apparatus employing my method may be used in 110 series, the products discharged from the first machines being re-treated on those succeeding, either for recleaning or for further treatment of the products produced in the first separation. Such a method of operation may be pursued in making three part separations, as in the washing of coal from 115 bone and slate.

Having described my invention, I claim:

1. A method of separating materials of 120 different specific gravity which consists in maintaining by agitation a uniformly distributed mixture of appreciably coarse granular material and liquid, whereby a fluid mass of relatively high specific gravity 125 and uniform composition is formed; introducing said materials into said fluid mass, permitting said materials to separate in said fluid mass and removing the resultant product of said separation from said fluid mass. 130

2. A method of separating materials of different specific gravity which consists in maintaining by agitation a uniformly distributed mixture of appreciably coarse granular material and liquid, whereby a fluid mass of relatively high specific gravity and uniform composition is formed; introducing said materials into said fluid mass; permitting the material of relatively low specific gravity to rise to the upper portion of said mass; permitting the material of relatively high specific gravity to sink to the lower portion of said fluid mass; and removing the materials, thus separated, from said fluid mass.
3. A method of separating materials of different specific gravity which consists in introducing said materials into a fluid mass of intermediate specific gravity, maintaining said fluid mass by agitating a uniformly distributed mixture of appreciably coarse granular material, and liquid; permitting the material of higher specific gravity than said fluid mass to sink to the lower portion of said mass; permitting the material of lower specific gravity than said mass to rise to the upper portion of said fluid mass; and removing the materials, thus separated, from said fluid mass.
4. A method of washing coal which consists in feeding said coal into a fluid mass of relatively high specific gravity, maintaining said fluid mass by agitating a uniformly distributed mixture of appreciably coarse granular material and liquid; permitting the coal of relatively low specific gravity to rise to the upper portion of said fluid mass; permitting the impurities of relatively high specific gravity to sink to the lower portion of said mass; and removing the coal and impurities, thus separated, from said fluid mass.
5. A method of washing coal which consists in feeding said coal into an agitated mixture of sand and water, composing a fluid mass of relatively high specific gravity; permitting the coal of relatively low specific gravity to rise to the upper portion of said fluid mass; permitting the sand and water to sink to the lower portion of said fluid mass; and removing the coal and impurities, thus separated, from said fluid mass; permitting the impurities of relatively high specific gravity to sink to the lower portion of said fluid mass; and removing the coal and impurities, thus separated, from said fluid mass.
6. An apparatus for the separation of materials of different specific gravity comprising in combination, a receptacle adapted to contain a fluid mass consisting of an agitated mixture of appreciably coarse granular material and liquid; a fluid mass consisting of said mixture in said receptacle; means for maintaining by agitation the fluidic properties of said fluid mass, whereby the separation is effected by differences in specific gravity and not by the classifying action of a current of liquid; means for introducing into said fluid mass the materials to be separated and means for removing said materials, after separation has been effected, from said fluid mass.
7. An apparatus for the separation of materials of different specific gravity comprising in combination, a receptacle adapted to contain a fluid mass consisting of an agitated mixture of appreciably coarse granular material and liquid; a fluid mass consisting of such mixture in said receptacle; means for maintaining by agitation the fluidic properties of said fluid mass, whereby the separation is effected by differences in specific gravity and not by the classifying action of a current of liquid; means for introducing into said fluid mass the materials to be separated; means for removing said materials, after separation has been effected, from said fluid mass and means for separating from said materials so removed portions of said fluid mass adhering thereto.
- In testimony whereof I have hereunto signed my name at Philadelphia, Pennsylvania, this first day of October 1915.
